PACKING RETAINER FOR JOURNAL
BOXES ON RAILWAY CARSOtto E. Wilson, Peru, Ind., and William H. Sale,
Sanston, Va., assignors to T-Z Railway Equipment
Co., Chicago, Ill., a corporation of Illinois

Application April 2, 1947, Serial No. 738,860

5 Claims. (Cl. 308—89)

1

The invention relates to packing retainers for journal boxes on railway cars.

The several objects of the invention are to provide a packing-retainer which: is adapted to efficiently confine the lubricant-saturated packing in the lower portion of the box under the journal and against outward rotation by the journal and movement toward the open end of the box; is adapted to provide a sturdy structure built up of substantially flat strips of metal; includes vertically rigid sections which are collapsibly connected for the insertion and removal of the retainer; is adapted to be firmly supported in its operative position in the journal box; includes parts adjustably connected for use of the retainer in journal boxes of different sizes, which includes side-bars provided with non-abrasive strips for preventing metal-to-metal contact with the journal; and other objects which will more fully appear from the detailed description.

The invention consists in the several novel features hereinafter set forth, and more particularly defined by claims at the conclusion hereof.

In the drawings:

Fig. 1 is a side elevation of the packing-retainer in its operative position in a journal box, the latter being shown in section.

Fig. 2 is a section taken on line 2—2 of Fig. 1.

Fig. 3 is a section taken on line 3—3 of Fig. 1.

Fig. 4 is a perspective view of the packing-retainer.

Fig. 5 is a plan view of a modified packing-retainer bar.

Fig. 6 is a side elevation of the bar shown in Fig. 5.

Fig. 7 is a section taken on line 7—7 of Fig. 5.

The improved packing-retainer is exemplified in a journal box of standard construction. The journal box comprises a body 10 provided at one end with the usual opening 11 for access to the interior of the box, and a cover 12 for said opening which is hinged at 13, to the top of the box. Journal 15 of an axle 16 extends through the inner end of the box and terminates near the outer end of the box with the usual flange 17. A "brass" or bearing block 18 engages the upper portion of the journal 15 and the usual wedge 19 engaging the top wall of the box body 10, holds the bearing block 18 in the box, as well understood in the art. A mass 20 of packing, usually cotton waste, is placed in the lower portion of the box under the journal and is kept saturated with lubricant for carrying lubricant to the rotating journal 15 for lubricating the surface which engages the block 18.

2

The improved packing-retainer comprises a support adjacent the end of the box, which is adapted to confine the packing to the under side of the journal and to prevent it working to the opening 11, and bars which are secured to the support, and extend longitudinally and at the sides of the journal, for preventing the packing from being carried around with the journal 10 and the bearing 18. This support comprises a pair of arcuate sections 22 and 23 formed of sheet or plate metal, which extend across the curved bottom of the box, under the journal 15 adjacent its front end. The plane of the sheet metal of sections 22 and 23 is vertical, to render them rigid. The inner or lower ends of sections 22, 23, are connected together by a bolt 24, which extends through elongated slots 25 and 26 in said members and is adapted to rigidly lock the sections together when the retainer is correctly positioned in the box. This bolt-and-slot connection, when the bolt is loosened, permits relative pivotal movement of the sections 22 and 23 for collapsing them for insertion and removal of the retainer through opening 11 in the box, and also permits relative sliding movement between said sections for their adjustment for use in journal boxes of different sizes. The sections 22 and 23 are provided with embossed portions 28, for stiffening purposes, and with feet or extensions 29, 30 which are adapted to engage and rest on the curved lower portion of the box body. Resilient strips 30 of flat metal, have their lower ends secured, for example, by rivets 43, to sections 22 and 23, respectively, are bowed as at 33 for vertical resiliency, and are provided at their upper ends with abutment-forming bends 34 which are adapted to seat against the usual lugs 35 which are used for holding the wedge 19 in the box, and the inside of the top wall of the box body adjacent the door. Strips 30 are also provided with outward extensions 36 below lugs 35, for depressing the bends to release them from lugs 35. Strips 30, when seated against lugs 35 and the top of the box, exert downward pressure on the vertically rigid sections 22 and 23, for causing the feet 29 to firmly engage the curved bottom of the box body and securing the support in its assigned position in the box. The sections 22, 23, when secured together, form a vertically U-shaped, rigid support which confines the packing under the journal and against outward movement.

The retainer comprises substantially rigid bars 38, which extend longitudinally of and along the sides of journal 15, and overlie the packing and prevent it from rotating with the journal. Each

of the bars 38, comprises a strip 40 of suitable fibrous or non-abrasive material, such as fiberboard, which is adapted to contact the rotating journal without scarring it. The strip 40 is secured between an angle strip 41 which may be integrally formed with one of sections 22 and 23, and a flat strip 42, which has its outer ends secured to a section 22, 23. Rivets 43 extend through the horizontal flanges of angle strips 41 and strips 40 and 42, and secure them together.

The operation of the improved retainer will be as follows: To insert the retainer in the journal box, bolt 24 which connects the sections 22 and 23, will be loosened and the upper ends of said sections and the resilient strips 30 will then be swung together. The resilient strips 30 will be flexed and collapsed sufficiently to permit the entire retainer to pass inwardly through the opening 11, the outline of which is indicated by the dotted line 11a. The bars 38 will be placed over the packing at the sides of the journal. Sections 22, 23, will be placed on the bottom of the box in front of the packing and the abutments 34 of resilient strips 30, will be sprung against the lugs 35. The feet 29 of members 22 and 23 will then be seated on the bottom of the box body and the resilient strips 30 will be secured in the seats formed at the shoulders 35 and the top wall of the box. When thus seated, the strips 30 will exert downward pressure on the stiff sections 22 and 23, so their feet 29 will firmly engage the bottom of the box body, and bars 38 will overlie the packing at the sides of the journal. After the retainer has been inserted in the box, the sections 22, 23, will be adjusted to position the side-bars 38 in the desired relation to the journal. The slot-and-bolt connection between members 22 and 23, permits adjustment of the bars 38 to and from each other, for accurately positioning them at the sides of the journal and for use in journal boxes of different sizes. After sections 22 and 23 and bars, have been set in their desired operative position, the bolt 24 will be tightened and secure them in rigidly locked relation for retaining the packing. When the retainer has been placed in the box, side bars 38 will overlie and press down the packing at the sides of the journal and prevent it from being carried to the bearing surfaces between the journal 10 and the bearing member 18. Sections 22 and 23 will confine the packing against forward displacement toward the opening 11 in the box. In this manner, the packing will be confined to the lower portion of the journal. The inner edges of the fiber strips 40 will be contiguous and may be set in close relation to the periphery of the journal, for effectively preventing any of the packing from being carried around to the bearing surfaces between the journal and bearing 18, and without marring the journal in event of side-swing of the journal in the box. The edges of strip 40 will not produce any abrasive effect on the periphery of the journal. When it is desired to remove or replace the packing 20 from the box, the resilient strips 30 will be depressed at the extensions 36 so that abutments 34 will clear lugs 35, bolt 24 will be loosened, and sections 22 and 23 and strips will be collapsed so that the entire retainer can be removed through the opening 11. The support 22, 23, extends to the bottom of the box and under the journal immediately adjacent its front end flange and serves to keep the packing out of the front portion of the box so that any free lubricant will be visible to the inspectors.

In the modification illustrated in Figs. 5-7, the side bars 40a for retaining the packing at the sides of the journal, are formed of an extension 44 on the sections 22, 23, and an integral underfolded strip 45. The extension 44 terminates outwardly of the strip 45, so there is but a single thickness of metal along the edge which is adjacent the journal. This construction provides flat rigid surfaces for efficiently holding down the packing. A corner bracket 46, resilient strips 30, and these bars, are secured together by rivets 44.

The invention exemplifies a packing-retainer for journal boxes which comprises a support formed mainly of plate or sheet metal to provide a sturdy construction. The invention also exemplifies a retainer with pivotally connected supporting sections which can be locked together, each carrying a packing-retainer side bar, the sections being adapted to be collapsed for insertion and removal of the retainer through the opening 11. The invention also exemplifies a retainer which includes vertically stiff supporting sections and flat resilient strips for pressing the said members downwardly against the bottom of the box body for firmly retaining the retainer in its assigned position in the journal box. The invention also exemplifies a retainer composed of sections which are adjustably connected for use in journal boxes of different sizes. The invention also exemplifies side bars for retaining the packing, which include side-bars with non-abrasive strips which will not abrade or mar the peripheral surface of the journal when contact occurs.

The invention is not to be understood as limited to the details described, since these may be modified within the scope of the appended claims without departing from the spirit or scope of the invention.

Having thus described the invention, what we claim as new and desire to secure by Letters Patent is:

1. The combination with a journal box for railway cars and a journal therein, of a packing-retainer comprising: a vertically rigid support extending across the lower portion of the box and under the journal, and provided with means for engaging the bottom of the box, resilient strips secured on the support, for releasably engaging the top of the box and pressing the support against the bottom of the box, and packing-retainer bars rigidly secured to said support and extending along the sides of the journal.
2. The combination with a journal box for railway cars, including a journal, of a packing-retainer comprising: a vertically rigid support extending around the lower portion of the box and under the journal, including adjustably connected sections provided with means for engaging the bottom of the box, means for locking the sections together, resilient strips secured on the sections, for releasably engaging the top of the box and pressing the support against the bottom of the box, and substantially rigid packing-retainer bars secured to said sections and extending along the sides of the journal.
3. The combination with a journal box for railway cars, including a journal, of a packing-retainer comprising: a vertically rigid support extending around the lower portion of the box and under the journal, including pivotally connected sections of sheet metal provided with means for engaging the bottom of the box, resilient strips secured on the sections, for releas-

ably engaging the top of the box and pressing the support against the bottom of the box, and packing-retainer bars rigidly secured to said sections and extending along the sides of the journal.

4. The combination with a journal box for railway cars, including a journal, of a packing-retainer comprising: a vertically rigid support extending around the lower portion of the box, including adjustably connected arcuate sections of sheet metal having embossed portions and provided with means for engaging the bottom of the box, resilient strips secured on the sections, for releasably engaging the top of the box and pressing the support against the bottom of the box, and packing-retainer bars rigidly secured to said sections and extending along the sides of the journal.

5. The combination with a journal box for railway cars and a journal therein, of a pack-

ing-retainer comprising: a support including pivotally connected sections, means for removably holding the sections in position in the box, packing-retainer bars of metal secured to said sections at the sides of the journal and provided with strips of non-abrasive material for extending along the sides of the journal, and means for locking the sections together in different positions to vary the spacing between the strips.
